UNITED STATES PATENT OFFICE

MAURICE HAZARD-FLAMAND, OF DOUAI, FRANCE

PROCESS FOR LIQUEFYING AND RECTIFYING AIR

Application filed October 9, 1929, Serial No. 398,459, and in France October 18, 1928.

This invention relates to the liquefaction of air.

It is not new to cause air to be liquefied to be compressed at a pressure of 200 atm. and 5 then to divide this air into two streams, one of which is expanded in the performance of work and the other by a throttle. It is also known to cool the air to be liquefied by means of a refrigerator.

10 It has been also proposed heretofore to divide the air into two streams, and to cool one of these streams by means of an additional refrigerator, the said stream being, however, compressed at a pressure lower 15 than that of the other stream.

According to the present invention, the cooling of the air compressed at 200 atm., which air is divided into two streams, is carried out by means of an additional refrigerator with liquefied gas, which is located in the circuit after the exchanger, but before the division into two streams of the air under pressure, all the mass of which is thus submitted to said cooling under the pressure of 25 200 atm.

The arrangement of the refrigerator between the exchanger and the point of the circuit where the division of the air takes place has the following advantages: at the 30 exhaust of the exchanger, the temperature of all the mass of air under pressure is reduced from 20° to approximately -10°. In known processes using an exchanger, the temperature of the air at the admission thereof into the expander is reduced to approximately -100°, which is disadvantageous; on the contrary, in the present invention, all the mass of compressed air, after its passage through the refrigerator, is cooled only to

35 approximately -50°, the temperature of admission of the air into the expander thus being raised from -100° to -50° without the necessity, as is the case for known processes, of removing the exchanger (which removal would cause a loss of cold at the exhaust of the counter current). This raise 40 determines an increase in the output of the outer expansion and said increase, added to the almost cost free auxiliary cold supplied 45 by the refrigerator (about 15 frigories per 50

kilog. of compressed air), approximately doubles the production of liquid air per horse-power of compression.

The cost free auxiliary cold, which can be caused to be absorbed by the compressed air 55 at the exhaust of an exchanger, is equal to the excess of its calorific power between about 20° and -50° over the amount of cold supplied by the counter current to the same. But this amount is so much weaker that the 60 specific heat and the weight of the counter current are less. It results therefrom that it is necessary to send into the expander only a counter-current which is entirely expanded. The raise of the pressure of the compressed air to 200° results in an increase in 65 the specific heat and the calorific capacity of the mass of this air. Besides, the increase in the liquefaction owing to this high pressure reduces the importance of the counter-current and, consequently, the amount of cold which is brought back into the system by the counter-current.

The process in accordance with the present invention is carried out in the manner 75 particularly described hereinafter, reference being had to the accompanying drawings, of which:

Fig. 1 is a diagrammatic view of apparatus used for effecting the liquefaction; 80

Fig. 2 illustrates diagrammatically how the liquefaction apparatus is combined with the rectification apparatus.

The air used for liquefaction is compressed at high pressure, for example, 200 atmospheres, by a compressor 1 and cooled in a water cooler 2. The air is then purified according to current practice and passed to an exchanger 3.

From exchanger 3 the air is conveyed to a 90 refrigerator 4 utilizing liquefied gas, for example, ammonia. After leaving refrigerator 4 the compressed and cooled air is divided into two parts. One part is led into a piston engine 9, in which it expands up to atmospheric pressure. The other part, under a pressure of 200 atm., passes through a liquefying exchanger 5 and upon leaving the same is expanded to atmospheric pressure 95 in an expansion vessel 6 through a tap, or 100

cock, 11. That portion of the expanded air which remains in a gaseous state is returned as a counter current to the exchangers, in conjunction with the exhaust of the expander 9 which may join the same either at the bottom of the liquefier 5, as shown, or in the expanding vessel 6. A cock 7 permits the liquefied air to be drawn off.

The liquefaction in the expander 9 is a very intensive one and could interfere with the operation thereof if suitable counter-acting provisions were not made, such as a tapping off device at the end of the piston stroke or a compounding with tapping off in the receiver. It may be desirable in some cases, even with a decrease in cooling action, to avoid complications in effecting reduction in condensation in expander 9. This result may be attained for example by lowering the pressure at which air is admitted to the expander by means of a cock or tap, 8, or by raising the temperature of admission of the air to motor 9, either at point 13 or partly at point 13 and partly at point 12.

In virtue of its arrangements and of its powerful output, the apparatus which has just been described is particularly well adapted to be coupled with one of the well known double column rectifiers.

It is well known that a prominent feature of this known rectifying apparatus consists in supplying to the lower column an excess of liquid nitrogen capable of rectifying in the upper column, at atmospheric pressure, a supplement of air exceeding about 30% of the quantity supplied to the lower column. Now, this quantity is usually about 30% greater than the exhaust of the expander of the liquefying machine associated with the column when the said machine is working at the rate of its maximum output.

It will therefore be possible, just as in other processes, to direct the exhaust of the condenser 5 into the lower column 17, either directly or through a concentrating coil 18, while, after complete expansion, the whole of the exhaust of the expander 9 will be directed upon the plate in the upper column 19. The excess of air to be rectified will be supplied to the rectifier by two compressors or a combined compressor 21 which will supply this partly compressed air into the lower column 17, and eventually partly at atmospheric pressure into the upper column 19. The counter-current of the liquefying apparatus will be secured by part of the nitrogen leaving the upper column 19.

What I claim is:

1. A process for liquefying air which comprises passing the air under high pressure through an exchanger and then through a refrigerator, dividing the air after it has passed through the refrigerator into two streams, expanding one of said streams in a low pressure liquefying chamber, expand-

ing the other of said streams in a work performing device operable by the expansion, returning the unliquefied air under low pressure from the liquefying chamber in heat exchange relationship to the air flowing to the liquefying chamber, and also returning the expanded, low pressure air from the work performing device in heat exchange relationship to the air flowing to the liquefying chamber.

70

75

2. A process for liquefying air as set forth in claim 1 in which the return of the low pressure air from the liquefying chamber and the work performing device is directed in heat exchange relationship to the air flowing to the liquefying chamber both before and after the air flowing to the liquefying chamber passes through the refrigerator.

80

3. A process as set forth in claim 1 in which the low pressure air after being returned in heat exchange relationship to the air flowing to the liquefying chamber is directed into apparatus for separating the air into its constituents oxygen and nitrogen.

85

In testimony whereof I hereunto affix my signature.

MAURICE HAZARD-FLAMAND.
